UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

HARP.

1,301,061.

Specification of Letters Patent.

Patented Apr. 15, 1919.

Application filed April 13, 1917. Serial No. 161,734.

To all whom it may concern:

Be it known that I, WALTER I. KIRK, a citizen of the United States, residing at Chicago, in the county of Cook and State of Illinois, have invented a certain new and useful Improvement in Harps, of which the following is a full, clear, concise, and exact description, reference being had to the accompanying drawings, forming a part of 10 this specification.

My invention relates to harps.

The principal object of the invention is to provide a construction by which the harp may be braced or strengthened, especially at 15 the upper part of the pillar and at the junction of the same with the neck.

A further object of the invention is to add security to the joint of the pillar and neck.

In carrying out the invention in accordance with the construction herein set forth, I provide a reinforcing device which is adapted to fit inside of the upper end of the pillar and to make a connection with the end of the neck which fits into the pillar, so 25 that the joint between the two parts is made perfectly secure and firm and at the same time the pillar is reinforced to prevent it from becoming bent or broken. This permits the neck to be made relatively small or 30 thin without any danger of disastrous results.

In the accompanying drawings Figure 1 is a view of a harp provided with a reinforcing device embodying my invention;

Fig. 2 is a perspective view of said reinforcing device.

Referring to the drawings I show a harp A having the usual pillar 1 and neck 2. The upper end of the pillar 1 is provided with a 40 longitudinally extending socket or recess 3 into which is fitted a reinforcing member 4. The latter may be of various forms or shapes but is preferably as shown in Fig. 2 and consists of a lower flat plate-like portion 4^a and 45 an upper socket portion 4^b. The portion 4^a is provided with apertures 5—5 for screws or other fastening devices and the sides of the socket portion 4^b are provided with apertures 6 and 7 respectively, for screws or 50 other fastening devices. The member 4 is secured in the socket or recess 3 with the socket portion 4^b opening toward the neck 2 so that the end portion 2^a of said neck fits into said socket member 4^b. Screws 8 are 55 passed through the side walls of the portion

4^b into the end 2^a and other screws 9 are passed through the apertures 5 in the plate portion 4^a so as to secure the device in position in the pillar 1. A cross piece 10 is preferably provided at the lower end of the 60 socket 4^b so as to form an abutment or shoulder for the end portion 2^a.

The pillar 1 is built up of several pieces and the reinforcing member 4 is secured to the left hand portion of the pillar before the 65 right hand portion is secured thereto.

In this way a firm and secure joint is provided and at the same time the harp is strengthened and reinforced.

It will be understood that changes and 70 modifications may be made without departing from the spirit of the invention.

What I claim is:

1. A harp having its pillar provided with a reinforcing member adapted to form a 75 connection for the neck.

2. A harp having its pillar provided with a reinforcing member having a socket receiving an end portion of the neck.

3. A harp having its pillar provided with 80 a longitudinally extending recess containing a reinforcing member which is provided with a socket receiving an end portion of the neck.

4. A harp having its pillar provided with 85 a longitudinally extending recess containing a reinforcing member which is provided with a socket receiving an end portion of the neck, the lower portion of said reinforcing member being flat and having apertures and 90 securing devices passing through said apertures.

5. A harp having its pillar provided with a longitudinally extending recess containing 95 a reinforcing member which is provided with a socket receiving an end portion of the neck, the lower portion of said reinforcing member being flat and having apertures for securing devices, and the socket portion of said member having its side walls provided with apertures for securing devices to pass into the end portion of the harp neck, and securing devices passing through said sets of apertures.

6. A harp having the upper portion of its 105 pillar provided with a longitudinally extending recess, a reinforcing member arranged in said recess and having a socket containing an end portion of the neck, means for holding said reinforcing member in po- 110

sition in the pillar and means for holding the end portion of the neck in position in said socket.

7. A harp having the upper portion of its pillar provided with a longitudinally extending recess, a reinforcing member arranged in said recess and having a socket containing an end portion of the neck, screws holding said reinforcing member in position in the pillar, and other screws holding said neck end portion in position in said socket.

8. A harp having the upper portion of its pillar provided with a longitudinally extending recess, a reinforcing member arranged in said recess and having a socket containing an end portion of the neck, and means for holding said reinforcing member in position in the pillar and the end portion of the neck in position in said socket, said reinforcing member also having a shoulder against which said neck end portion fits and rests.

9. A harp having the upper end of its pillar provided with a recess, and a reinforcing member secured in said recess, said reinforcing member having a socket receiving

an end portion of the harp neck, and also having a shoulder forming the lower end of said socket, said shoulder providing an abutment upon which the harp neck end portion rests.

10. A harp having the upper end portion of its pillar provided with a recess, a reinforcing member 4 arranged in said recess, 35 said reinforcing member having a flat lower portion 4^a and an upper box-like portion 4^b forming a socket open at the top and at one side and closed at the bottom by a cross piece 10, the end portion of the harp neck 40 being fitted into said box-like portion and resting upon said cross piece 10, screws passed through the flat portion 4^a to hold said reinforcing member in position and other screws passing through the walls of said box-like portion 4^b and holding the end portion of said harp neck in position therein.

In witness whereof, I hereunto subscribe my name this 21st day of March, A. D. 1917.

WALTER I. KIRK.
